Inventor:

UNITED STATES PATENT OFFICE.

BENJAMIN GOOCH, OF SCIO, OREGON.

DISPENSING-CAN.

1,110,682.

Specification of Letters Patent.

Patented Sept. 15, 1914.

Application filed October 23, 1912. Serial No. 727,426.

To all whom it may concern:

Be it known that I, BENJAMIN GOOCH, citizen of the United States, residing at Scio, in the county of Linn and State of Oregon, have invented certain new and useful Improvements in Dispensing-Cans, of which the following is a specification, reference being had therein to the accompanying drawing.

This invention relates to an improvement in dispensing cans, and one of the primary objects of the present invention is the provision of a simple and efficient device of this character in which compressed air is utilized as the medium for causing the flow of liquid through the discharge tube of the dispensing can.

A further object of the present invention is the provision of a dispensing can of this character, all of the parts of which are contained within a suitable tank which is so constructed that it may be readily transported from place to place.

A further object of the present invention is the provision of a device of this character in which the pump for creating an air pressure within the tank is carried by the tank closure which is removable so that access can be readily had to all parts of the device to enable the same to be cleaned and kept in a sanitary condition.

Other objects of the invention will be apparent from the detailed description herein-after, when read in connection with the accompanying drawings forming a part hereof, wherein a convenient embodiment of the invention is illustrated and wherein like characters of reference refer to similar parts in the several views.

In the drawings: Figure 1 is a longitudinal section of the improved dispensing can; Fig. 2 is a top plan view of the improved dispensing can.

Referring now more particularly to the drawings, A designates a metal tank, conveniently cylindrical in shape, which is adapted to contain the liquid which is to be used with the dispensing can. The tank A is provided with suitable supporting legs a extending from the bottom thereof and secured to the underside of the bottom of the tank are guide ways b b which extend transversely thereof and are adapted to removably support a holder B which is adapted to support an alcohol or other lamp B' which may be of any well known construction.

By the construction above described it is possible, when it is found desirable to do so, to heat the liquid contents of the tank by means of the lamp B' and in order that the liquid may be heated to any desired temperature, a thermometer C is secured to the exterior of the tank in any suitable manner, the bulb of said thermometer conveniently extending through the wall of the tank and into the liquid contained therein. By means of the guide ways b b which are provided on the underside of the bottom of the tank, it will be seen that the lamp holder B can be readily slid therein so as to readily enable filling and lighting of the lamp B' when it is found desirable to use the same.

The upper portion of the tank A is open and a closure D is provided therefor which has a threaded engagement with the upper end of the tank so that it may be readily secured in position and removed from the tank when it is desired to fill or clean the same. If desired, packing may be interposed between the closure D and the adjacent portion of the tank A to insure an air tight joint between the parts when the closure is secured in position. The closure D is provided with an opening in the central portion thereof and fitting within said opening and depending from the closure is an air pump cylinder E within which is adapted to work a piston E' which may be of any desired construction. The upper end of the pump cylinder E is closed by a cylinder head E² which has a threaded engagement with the upper end of the cylinder so that it may be readily removed when it is desired to clean the cylinder or to obtain access to the piston therein. Extending upwardly from the closure D adjacent the periphery thereof is a rigid upright f to the upper end of which is pivotally connected in any suitable manner one end of a pump operating lever F, which extends transversely across the top of the closure, and the free end of which is bent downwardly into proximity to the closure and terminates in an outwardly bent portion f'. Pivotally connected to a collar intermediate the ends of the lever F is a piston rod G which extends downwardly through an opening e formed in the removable cylinder head E² and the lower end of which is pivotally connected in any suitable manner to the pump piston E'. The opening e in the cylinder head E² is slightly greater in diameter than

the piston rod G so as to provide a port for the admission of air into the pump cylinder E when the piston E' is moved downwardly therein. The piston E' is provided with 5 any suitable form of valve e' therein which will permit the passage of air therethrough when the same is moved upwardly in its cylinder and will be closed when the piston is moved downwardly in its cylinder. The 10 closure D of the device is provided adjacent the free end of the pump operating lever F with a loop d which is pivoted thereto so that when the lever is in its lowermost position, said loop may be moved over the laterally projecting end portion f' thereof. When the free end of the lever is engaged by the loop d in this manner, it will be seen that the piston E' cannot be moved in the cylinder of the air pipe and that such lever 15 can be used as a handle for carrying the apparatus from place to place. It will also be seen that when locked in this manner the lever can be used as a handle for threading the closure D into the upper end of the tank 20 A and for removing the same therefrom.

The closure D of the device is provided with a pressure gage H which may be of any well known construction and which is designed to indicate the air pressure in the 25 upper portion of the tank. The closure is also provided with a safety valve H' which may be of any well known construction and which is adapted to permit the escape of air from the upper portion of the tank should an excessive pressure be reached. The lower portion of the tank A is provided 30 with an outlet pipe A' to which is adapted to be connected the ordinary syringe tube A² and in which pipe is interposed a stop cock A³ enabling the flow of liquid from the tank through the syringe tube to be controlled. As the closure D carries the air pump and all of the operating parts therefor, and as such closure is removably secured in the upper portion of the tank, it 35 will be seen that access can be readily had to all of the various parts of the apparatus and that the same can be readily maintained

in a clean sanitary condition. It will also be seen that as the air cylinder is provided with 50 a removable head that when it is desired to do so, access can be had to all parts of the interior of such cylinder and the piston contained therein.

It is believed that the operation and use 55 of the device will be obvious from the description hereinbefore contained.

While a convenient embodiment of the invention is illustrated in the accompanying drawings, it will be understood that 60 many changes may be made to the particular form and construction therein shown without departing from the spirit and scope of the invention as defined in the appended claim. 65

I claim:—

In a device of the character described, a tank adapted to contain a liquid, said tank being open at its upper end and being provided with a liquid outlet pipe in communication with the lower portion thereof, a closure removably secured to the upper end of said tank, an air pump cylinder depending from said closure and in communication with the upper portion of said tank, a piston 70 adapted to work in said air pump cylinder, a relatively short upright extending upwardly from one edge of the closure, a pump operating lever pivotally connected to the top of said upright, and extending transversely entirely across the closure, a collar mounted on said operating lever, a piston rod extending from said piston and pivotally connected to said collar, a pivoted locking pin secured to the closure at the opposite end and adapted to swing over the free end of the operating lever to lock the same to the closure so as to form a handle for the receptacle. 75

In testimony whereof I affix my signature 80 in presence of two witnesses.

BENJAMIN GOOCH.
